MOORED MINE AND MAGNETICALLY ACTUATED FIRING MEANS THEREFOR

Morton Stimler, Hyattsville, Md., assignor to the United States of America as represented by the Secretary of the Navy

Application March 31, 1958, Serial No. 725,455

8 Claims. (Cl. 102—18)

(Granted under Title 35, U.S. Code (1952), sec. 266)

The invention described herein may be manufactured and used by or for the Government of the United States of America for governmental purposes without the payment of any royalties thereon or therefor.

This invention relates to a moored marine mine and more particularly to a moored mine having a plurality of magnetic devices carried thereby for firing the mine in response to movement thereof away from the mine when at least one of the devices has become magnetically attached to a moving vessel.

In devices of this type heretofore proposed it has been the usual practice to provide the mine with a plurality of projections or antennae projecting therefrom containing ampules having a quantity of acid therein and adapted to fire the mine as the ampules are broken by contact with a vessel or a large fish, as the case may be. In certain other types of prior art mines, contact of the vessel with an electrode carried by the mine or secured thereto causes the mine to be fired by sea battery action or otherwise. While these devices have proved generally satisfactory under most conditions of service they are subject to accidental firing by contact with a large fish.

The device of the present invention possesses all of the advantages of the prior art devices of this general character in which the mine is actuated by actual contact with the hull of the vessel and in addition thereto possesses the additional advantage of simplicity and reliability in operation and the additional advantages of an initial low cost.

In accordance with the present invention the moored mine is provided with a plurality of outstanding antennae, each of which has a permanent magnet movably carried at the outermost extremity thereof and of sufficient strength to actuate a firing switch to closed position when the magnet becomes attached magnetically to the hull of a moving vessel, as will more clearly appear as the description proceeds.

One of the objects of the present invention is the provision of a moored mine having a new and improved magnetically actuated firing mechanism therein.

Another object is to fire a mine in response to movement of a permanent magnet carried thereby as the magnet moves away from the mine by magnetic attraction to the hull of a moving vessel.

Still other objects, advantages and improvements will become apparent from the following description taken in connection with the accompanying drawings of which:

Fig. 1 is a view in diagrammatic form of a pair of moored mines employing the firing mechanism of the present invention according to a preferred embodiment thereof;

Fig. 2 is an enlarged view partially in section and partially broken away of one of the mines of Fig. 1;

Fig. 3 is a greatly enlarged view in section of the magnet element secured to the hull of a vessel by magnetic attraction and the supporting means therefor interconnecting the magnet with the mine;

Fig. 4 is a sectional view of a firing switch suitable for

2

operation by movement of the magnet of Fig. 3 away from the mine; and

Fig. 5 is a firing circuit suitable for use with the device of the present invention.

Referring now to the drawings on which like numerals of reference are employed to designate like or similar parts and more particularly to Fig. 1 thereof, there is shown thereon a pair of moored mines each indicated generally by the numeral 10 and preferably having an arm 11 secured thereto at one end thereof for establishing a mooring connection by way of cable 12 to anchor 13. The mine is provided with a flotation chamber constructed and arranged in such a manner as to maintain the mine in a horizontal position within the water when the mine is moored. The uppermost mine, as viewed in Fig. 1, is moored at a depth beneath the surface of the water sufficient for engagement with the hull of the vessel 14 and the lowermost mine is of a depth adapted to be engaged by the hull of a submarine such as the submarine 15 illustrated.

As more clearly shown on Fig. 2, the mine comprises a cylindrical casing 16 having an explosive charge 17 therein adapted to be fired by the operation of an electro-responsive detonator 18 as a firing current is applied thereto. The explosive charge 17 is contained within a chamber 19 defined by the casing 16 and a partition or wall structure 21 in such manner as to leave a buoyancy space or chamber 22 sufficient to maintain the mine in a horizontal moored condition.

The mine is provided with a plurality of antennae generally indicated at 23, each of the antennae comprising a flexible hose-like member 24 composed of rubber or any of the synthetic varieties thereof suitable for the purpose and having one end thereof secured as by clamp 30 to a nipple 25 projecting outwardly from the mine casing and secured thereto in any convenient manner as by welding the parts together. The other end of the hose-like member is disposed within a bore 26 formed within connector 27 and secured thereto in any suitable manner as by the clamp 28 threaded thereon to which the elongated hose member 24 is clamped as by the bolts 29, Fig. 3. The connector 27 is provided with a second bore 31 within which is slideably disposed a guide or plunger 32 having a rod 33 connected thereto and looped at the outer end thereof for pivotal engagement with eye bolt 34. The plunger 32 is yieldably maintained in a retracted position by spring 35 until moved therefrom by a pull on permanent magnet 36 to which eye bolt 34 is connected as by the nut 37. The spring 35 is maintained in a compressed condition by a cap 38 having an aperture 39 therein of sufficient size to allow free sliding movement of rod 33 therein, the cap being secured to the connector in any suitable manner as by the bolts 41. The plunger 32 is connected by a thin flexible line 42 secured thereto to a firing switch 43 preferably disposed within the mine casing and secured thereto as by the bolts 44, Fig. 4.

The firing switch may be of any type suitable for the purpose, such for example, as the switch illustrated in which a lever arm 45 actuates a pair of contacts to closed position in response to a force applied thereto, movement of the arm to an initial position causing the contacts to open. The lever arm 45 is preferably enclosed within a flexible jacket or sleeve 46 having an extension 47 formed thereon to which one end of the line 42 is secured, a retractile spring 48 being employed to yieldably maintain the switch arm in an initial unoperated position until moved therefrom by a force or pull applied to line 42. The jacket 46 is formed preferably integral with a gasket 49 disposed between a clamping member 40 held by the screws 44 and the surface of wall 51 to provide a watertight connection therebetween and prevent entrance of

the water into the switch 43. The switch is provided with a pair of terminals 52 for establishing a plurality of external electrical connections thereto.

There is also provided within the casing 16 a hydrostat indicated generally by the numeral 53, Fig. 2, adapted to close arming switch 54 at the expiration of a predetermined interval of time after the mine has been planted. A battery 55 is secured to the inner casing of the mine and operatively connected to the hydrostatically controlled switch 54 and the firing switches 43. For a more complete understanding of this wiring arrangement, reference is now had to Fig. 5 on which is shown in diagrammatic form a circuit arrangement suitable for use with the device of the present invention in which the battery 55 is connected at one terminal thereof to one contact of arming switch 54 from whence the circuit is continued to one terminal of detonator 18 and thence by way of the firing switches 43 in parallel to the other terminal of battery 55.

From the foregoing it will be apparent that after the mine has been moored and the arming switch 54 thereof closed by hydrostatic pressure, the mine will be fired by operation of any of the switches 43 as the magnet 36 thereof is pulled away from the outer end of the antenna by magnetic attraction to the hull of a moving vessel. When this occurs a circuit is closed to fire the detonator and explode the mine.

While the invention has been described with particularity with reference to a cylindrical mine which has a pair of antennae diametrically disposed projecting from one end portion thereof and a second pair of antennae diametrically disposed and projecting exteriorly from the other end of the mine, it is not so limited as, if desired, the mine may be spherical or of other outward configuration and various arrangements of antennae and various different numbers of antennae may be employed, if desired. Furthermore, while the invention has been described with reference to a pair of mines moored by a single mooring cable, it will be understood that this has been done for the purpose of illustration and that the number of mines moored by the anchor may be greater or less than the number illustrated.

Whereas the invention has been described with particularity with reference to one example thereof which gives satisfactory results, it is not so limited as it will be understood by one skilled in the art, after understanding the invention, that various changes and modifications may be made without departing from the spirit and scope of the invention, and it is intended therefore, in the appended claims, to cover all such changes and modifications.

What is claimed as new and desired to be secured by Letters Patent of the United States is:

1. In a marine mine, in combination, a buoyant mine, means including a cable for mooring the mine within a body of water at a depth less than the draft of a target vessel, a plurality of antennae projecting outwardly from said mine and secured thereto, each of said antennae comprising a flexible elongated tubular member, a swivel connector secured to the uppermost end portion of each of said antennae, a permanent magnet carried by the outwardly extending end portion of said connector and movable pivotally about any one of a plurality of axes and outwardly with respect thereto, a firing switch disposed within said mine, and a flexible line disposed within said tubular member interconnecting the magnet with said firing switch for causing the switch to be actuated to a firing position in response to movement of the magnet away from the end of said antenna by magnetic attraction between the magnet and the hull of a moving vessel as the vessel moves away from the mine while the mine is moored.

2. A firing mechanism for a moored mine comprising, in combination, a mine casing, means including a cable

for mooring said casing at a predetermined depth of submersion less than the draft of a target vessel, a plurality of flexible antenna elements carried by said casing and projecting outwardly therefrom, each of said elements having a swivel connector secured to the outermost end portion thereof, a permanent magnet carried by said connector at an end portion thereof and movable pivotally and outwardly with respect thereto in response to magnetic attraction between the magnet and the hull of a vessel as the magnet makes contact therewith and the vessel moves away from the mine while the mine is moored, means for yieldably maintaining the magnet in an initial position relative to said connector, a firing switch disposed within said casing, and means including a flexible line disposed within said tubular member for establishing an operative connection between said magnet and the firing switch for causing the firing switch to be closed as the magnet is moved a predetermined distance from said end portion of the connector.

3. A firing mechanism according to claim 2 in which said antennae are arranged in pairs at predetermined intervals on said casing, each of said pair of antennae being arranged in diametrically disposed relation with respect to said casing and in predetermined uniform spaced relation therealong.

4. A firing mechanism according to claim 3 in which means are provided for yieldably maintaining the firing switch in an initial unoperated position.

5. In a moored mine, in combination, a cylindrical mine casing, means including a cable for mooring said casing beneath the surface of a body of water at a depth of submergence less than the draft of a target vessel, a pair of diametrically disposed flexible antennae secured to the mine casing and projecting outwardly therefrom, at least one additional pair of flexible antennae secured to the mine casing and projecting outwardly therefrom in predetermined spaced relation with respect to the first named pair of antennae, a permanent magnet individual to each of said antennae, means including a swivel for yieldably and pivotally securing the magnet to an outwardly projecting end portion of the antenna for movement away from the end thereof as the magnet engages the hull of a moving vessel while the mine is moored, a plurality of firing switches equal in number to the number of antennae, and means including a flexible line disposed within a respective one of said antennae and interconnecting each of the firing switches with a respective magnet for operating the firing switch to a closed position as the magnet connected thereto is moved away from the end of the antenna.

6. A system for destroying an enemy surface vessel and undersea craft comprising, in combination, an elongated cylindrical mine having a buoyancy chamber therein so arranged as to maintain the mine in a horizontal position when moored beneath the surface of the water, a mine anchor, a mooring line connected to said anchor and to one end of the mine and of sufficient length to maintain the mine completely submerged at a depth less than the depth of the keel of a target surface vessel, a second cylindrical mine having a buoyancy chamber therein so arranged as to maintain the mine in a horizontal moored position within the water, means for connecting said second mine to the mooring cable intermediate the first named mine and the anchor at a depth of submersion such that it is adapted to be contacted by a submerged underwater craft, each of said mines having a plurality of flexible tube-like antennae secured thereto and projecting outwardly therefrom, means for connecting one end of each of said antennae to the mine such that the connected ends of each antennae extend outwardly in a radial direction from the axis of the mine, a connector comprising a rigid cylindrical member clamped in watertight connection to the upper end of each of said antennae, a plunger having an eye formed in the outer end

thereof slideably disposed within said member, means including a spring within the member for maintaining said plunger yieldably in a normal retracted condition, a U-shaped magnet swivelly connected to said eye at the mid-portion thereof and adapted to engage the surface of a moving vessel with sufficient force to retract said spring and move the plunger outwardly as the vessel moves relative to the mine, means including a plurality of normally open interconnected switches for firing the mine when any one of said switches is closed, said switches being equal in number to the number of said antennae and carried by the mine interiorly in a position opposite the inner end portion of the antenna respectively associated therewith, and a plurality of flexible lines respectively disposed within the antennae for establishing an operative connection between the inner end of said plunger and the switch associated with the antenna carrying the connector within which the plunger is disposed for closing the switch when the plunger is moved to an outwardly extending position with respect to the

20

connector by the permanent magnet swivelly connected thereto in response to movement of the target vessel to which the permanent magnet is attached with respect to the mine while the mine is moored.

5 7. A system according to claim 6 in which the antennae are arranged in pairs, the antennae of each of said pairs being arranged diametrically on opposite sides of the mine.

10 8. The system of claim 7 in which the pairs of antennae are each disposed at different positions along the axis of the mine and are oriented angularly about the axis of the mine in such manner that each pair of antennae is positioned at a different angle at the point of connection thereof with the mine from each of the other 15 pairs of antennae.
